H. B. BEETZ

TACK PULLER

Filed Sept. 22, 1923

Fig. 1.

INVENTOR
HANS B. BEETZ

BY Dewey, Strong, Townsend & Loftus
ATTYS.

UNITED STATES PATENT OFFICE.

HANS B. BEETZ, OF SAN FRANCISCO, CALIFORNIA.

TACK PULLER.

Application filed September 22, 1923. Serial No. 664,220.

To all whom it may concern:

Be it known that I, HANS B. BEETZ, a citizen of the United States, residing at the city and county of San Francisco, and State of California, have invented new and useful Improvements in Tack Pullers, of which the following is a specification.

This invention relates to tack and nail pulling devices of the portable type.

10 It is the principal object of the present invention to generally improve devices of the character referred to, whereby to provide an efficient portable tack puller of simple and inexpensive construction and which may 15 be employed to rapidly remove tacks and the like from surfaces into which they are driven.

20 In carrying out this object I provide a flat base plate carrying a revoluble extracting member, which plate may be manually guided to bring the extracting member into operative engagement with tacks projecting from a surface into which they are driven, to permit the extracting member to extract the tacks and discharge them into a 25 receptacle also carried by the base plate.

One form which the invention may assume is exemplified in the following description and illustrated by way of example in the accompanying drawings, in which:—

30 Fig. 1 is a perspective view of a device embodying the preferred form of my invention.

Fig. 2 is an enlarged side elevation of the extracting member.

35 Fig. 3 is an end elevation of the same disclosing its construction.

Referring more particularly to the accompanying drawings, 10 indicates a flat base plate which is formed with a tapered end 12. The tapered end is formed with a 40 centrally located divergent recess 14. Mounted directly above this recess is a revoluble extracting wheel 15 which is formed with teeth 16 for engaging the heads of tacks entering the recess 14 to extract them from the surface from which they project. Reference being had to Fig. 3, it will be seen that the wheel 15 is centrally grooved so that the teeth 16 thereon will engage the heads of 45 the tacks at each side of the body thereof.

The wheel 15 is secured on a shaft 17 which is journaled in bearings 18 fixed to the base plate 10. One end of this shaft is fitted with a bevel gear 19 which meshes with a bevel pinion 20 fixed on a drive shaft 21. This 50 drive shaft is journaled in bearings 22 and

is fitted with a worm gear 23 which meshes with a worm 24 fixed on the shaft of an electric motor 25. This motor is fixed on the base plate and is provided with an extension cord by which it may be electrically connected to a suitable source of electrical energy.

At the rear of the base, a handle 26 is provided and by which the device may be manually guided to bring the extracting wheel into operative engagement with tacks projecting from a surface.

In operation of the device, assuming that the motor is running, the device is guided 70 along a surface from which tacks project to position the tacks within the recess 14. The teeth on the extracting wheel will engage the underside of the heads of the tacks and will extract and discharge them into the open 75 front end of a receptacle 28 carried by the base plate 10.

The front end of the base plate is sharpened so that it may be employed to pry up tacks driven into a surface with their heads almost 80 flush therewith.

As the bottom of the base plate is smooth it will not injure any surface over which it may be guided.

From the foregoing it is obvious that an 85 efficient portable tack puller has been provided which may be employed to rapidly extract tacks from a surface into which they are driven.

Having thus described the preferred form 90 of my invention, it is to be understood that various changes in its construction may be made without departing from the invention as defined in the appended claims.

Having thus described my invention, what 95 I claim and desire to secure by Letter Patent is:—

1. A portable tack puller comprising a flat base having a recess formed therein for engaging tacks, a revoluble extracting member carried by the base above said recess and adapted to engage and extract tacks, and means carried by the base and operatively connected to the extracting member for revolving the same.

2. A portable tack puller comprising a flat base plate having a recess formed in one end thereof, a revoluble extracting member carried by the base plate and positioned above said recess to engage and extract tacks entering the same, an electric motor carried by the base plate and operatively connected to

the extracting member to drive the same, and a receptacle carried by the base plate adapted to receive tacks extracted by the extracting member.

5. A portable tack puller comprising a flat base plate having a converging recess formed in one end thereof, a revoluble toothed wheel carried by the base plate and positioned above the recess to engage and extract tacks 10 positioned therein, a receptacle fixed on the base at the rear of said wheel and having an open end into which the extracted tacks may be discharged by said wheel, an electric motor on the base and operatively connected 15 to said wheel for revolving the same, and a handle on the base plate whereby it may be manually guided.

4. A portable tack puller comprising a base having a recess formed in one end thereof, 20 of, a revoluble extracting member carried

by the base and positioned above said recess to engage and extract tacks entering the same, and an electric motor carried by the base and operatively connected to the extracting member for revolving the same.

5. A portable tack puller comprising a base having a recess formed in one end thereof, 25 a revoluble extracting member carried by the base and positioned above said recess to engage and extract tacks entering the same, 30 said extracting member comprising a toothed wheel having a circumscribing groove formed centrally in the circumferential face thereof whereby the teeth on said wheel will engage the under side of the heads of the 35 tacks, and an electric motor carried by the base and operatively connected to the extracting member for revolving the same.

HANS B. BEETZ.
